UNITED STATES PATENT OFFICE.

PELEG JAMES CONGDON, OF CRANSTON, RHODE ISLAND.

LACING.

SPECIFICATION forming part of Letters Patent No. 748,703, dated January 5, 1904.

Application filed February 4, 1902. Serial No. 92,597. (No model.)

To all whom it may concern:

Be it known that I, PELEG JAMES CONGDON, of Cranston, in the county of Providence and State of Rhode Island, have invented certain new and useful Improvements in Lacings; and I do hereby declare the following specification, taken in connection with the accompanying drawings, forming a part of the same, to be a full, clear, and exact description thereof.

The invention relates to lacings for shoes, corsets, and the like, and particularly to the application of a metallic stiffener to the end of a tubular lacing.

The invention consists of certain features and combinations of parts hereinafter described and claimed.

Referring to the drawings, Figure 1 is a perspective view of a flat tubular lacing embodying my invention. Fig. 2 is a plan view of a flat metallic stiffener. Fig. 3 is a plan view of a portion of a flat tubular lacing with the metallic stiffener inserted in the end thereof. Fig. 4 is a transverse section on the line 1 1, Fig. 3. Fig. 5 is an edge view showing the end of the lacing folded over. Fig. 6 is a plan view showing the end of the lacing with the lacing and the inclosed stiffener bent into U form. Fig. 7 is a transverse section on the line 2 2, Fig. 6. Fig. 8 is a plan view of a metallic stiffener bent into U form before being inserted into the end of the lacing. Fig. 9 is a plan view, and Fig. 10 an edge view, showing the end of the lacing flattened at right angles to the body of the lacing and cut at an angle. Fig. 11 is a plan view showing a U-shaped stiffener inserted in the end of the lacing shown in Fig. 10. Fig. 12 is a transverse section on the line 3 3, Fig. 11. Fig. 13 is a plan view showing the upper face of the lacing depressed into the opening of the stiffener and with the end folded over. Fig. 14 is a transverse section on the line 4 4, Fig. 13. Fig. 15 is a view showing the completed tip; and Fig. 16 is a transverse section on the line 5 5, Fig. 15, Figs. 2 to 16, inclusive, being on a larger scale than Fig. 1.

The fabric A of which the lacing is composed is a flattened tubular fabric. A metallic stiffener B, preferably provided with rounded ends, as shown in Fig. 2, is inserted in the end of the tubular fabric A, with the

end of the fabric extending a short distance beyond the end of the stiffener, as indicated in dotted lines in Fig. 3. The projecting end 55 of the fabric is then folded over, as shown in Fig. 5, and then the stiffener and fabric are rolled or bent into the form shown in Figs. 6 and 7. If preferred, the metallic stiffener B may be bent into U form, as shown 60 in Fig. 8, before it is inserted in the end of the tubular fabric, in which case the projecting end of the fabric is folded over and tucked into the opening of the U-shaped stiffener, and the upper side or layer of the 65 body of the fabric is depressed into said opening, thereby drawing the lower side or layer of the tubular fabric snugly around the U-shaped stiffener, as shown in Fig. 7. Pressure is then applied to cause the edges 70 of the U-shaped stiffener to approach each other to close the opening and complete the tip into the form shown in Figs. 15 and 16. As will be seen, the metallic stiffener in the completed tip is in the form of a split tube, 75 and the folded-over end of the tubular fabric and the side edges thereof are clamped in the split in the tube, whereby the metallic stiffener is firmly and securely held in place in the end of the tubular lacing, and a tip is 80 provided in which the metallic stiffener is entirely concealed from view, being covered and surrounded by the fabric of the lacing.

In Figs. 9 to 16, inclusive, is shown an improved method of applying the metallic stiffener to a tubular lacing which facilitates the operation and produces a neater appearance in the finished article. The end of the tubular fabric is flattened at right angles to the body of the fabric, as shown at a, Figs. 9 and 90 10, and the end of the fabric is then cut diagonally or at an angle, as shown at b in said figures. The end of the fabric is then flattened back to its original position and the U-shaped stiffener inserted in the end of the 95 tubular fabric in the position shown in Fig. 11. As will be seen from said figure, there is much less fabric projecting beyond the end of the stiffener and less fabric to be folded over, the upper layer of the tubular fabric 100 beyond the end of the stiffener being entirely removed and the lower layer being materially cut away and narrowed. There is therefore only the narrowed end of the lower layer to

be folded over and tucked into the opening of the stiffener. The upper layer of the fabric is depressed into the opening of the stiffener, as shown in Figs. 13 and 14, and the 5 tip is completed in the same manner as before into the finished form, as shown in Figs. 15 and 16.

With the method last described there is, as above stated, less fabric to be folded over 10 and tucked into the end of the stiffener, and the end of the finished tip will be correspondingly smaller and neater in appearance, while at the same time the folded-over end of the fabric, as well as the side edges thereof, will 15 be firmly clamped and held in the split of the split tube formed by the stiffener, and said stiffener will be securely held in the end of the tubular fabric and will be entirely covered and concealed from view.

20 While it is preferred for convenience to bend the metallic stiffener in a **U** shape before it is inserted in the end of the tubular fabric, it will be understood that in both of the methods above described it is immaterial, 25 so far as the main feature of the invention is concerned, whether the stiffener be thus first bent or whether the metallic stiffener is inserted in a flat form into the end of the fabric and the stiffener and fabric then bent or 30 rolled up together.

What I claim as my invention, and desire to secure by Letters Patent, is—

1. A tubular lacing having a stiffener inserted in the end of the tubular fabric comprising the lacing and held in place therein by having the side edges of the fabric clamped by the stiffener, substantially as described.

2. A tubular lacing having a stiffener inserted in the end of the tubular fabric comprising the lacing and held in place therein by having a folded-over end portion of the fabric and the side edges thereof clamped by the stiffener, substantially as described.

3. A tubular lacing having a stiffener inserted in the end of the tubular fabric comprising the lacing, said stiffener being in the form of a split tube with one layer of the fabric tucked in the opening of the tube and with the side edges of the fabric clamped by the 50 tube, substantially as described.

4. A tubular lacing having a stiffener in-

serted in the end of the tubular fabric comprising the lacing with the end of the fabric cut at an angle and with said cut end folded over into and clamped by the stiffener, substantially as described.

5. A lacing-tip comprising a tubular lacing and a plate incased within the tubular fabric end thereof, the two layers of the fabric and the plate forming a unitary longitudinally-bent structure, substantially as described.

6. A lacing-tip comprising a tubular lacing and a metallic plate incased within the tubular fabric end thereof having both of its sides covered by the fabric, the two layers of the 65 fabric and the plate forming a unitary longitudinally-bent structure having the fabric covering the longitudinal edges of the plate, substantially as described.

7. A lacing-tip comprising a tubular lacing 70 and a metallic plate incased within the fabric end thereof, said plate and two layers of fabric being compressed transversely to form the lacing-tip, substantially as described.

8. A tubular lacing, short metallic plates 75 in the tubular ends thereof, a single section or portion of the tubular lacing covering both sides of each of said plates, said plates and ends being bent longitudinally of the lacing to present in cross-section an outer covering 80 of fabric, a bent metallic plate and two thicknesses of fabric in the space between the bent portions of the metallic plate, substantially as described.

9. A lacing-tip comprising a tubular lacing 85 and a metallic plate incased within a tubular end thereof, said plate and the layers of said end being pressed together closely, transversely to form the lacing-tip and having the fabric covering the longitudinal edges of the 90 plate, substantially as described.

10. Lacing-tips, comprising the tubular ends of a seamless tubular lacing, a short oblong metallic plate snugly fitted in each of said ends when in the flat, said plates and said 95 ends forming when folded longitudinally in the finished product substantially circles in cross-section, substantially as described.
